DOUBLE PIPE HEAT EXCHANGER

John C. Mahoney, Westfield, N. J., assignor to
 Henry Vogt Machine Co. Inc., Louisville, Ky., a
 corporation of Kentucky

Application June 16, 1936, Serial No. 85,614

2 Claims. (Cl. 257—247)

This invention relates to double pipe heat exchangers of the type in which the pipes are arranged in multiple tiers or rows and connected serially at their ends.

The general object of the invention is to provide a double pipe apparatus for the indirect exchange of heat between fluids, which can be completely and rapidly disassembled for purposes of cleaning or inspection, and in which the inner tubes are free floating. Hence the tubes may vary in length according to temperature without setting up untoward strains in the structure of the heat exchanger. Heretofore in double pipe exchangers it has been the general practice to provide for expansion by using a packed joint or gland in which the inner tube can move as its length changes with temperature. Such exchanger designs can be disassembled for cleaning but the process of removing the inner tubes is labor-consuming and usually entails the expense of replacing damaged gland packing. Further such designs are not adapted to operation under high pressures or high temperatures. Where devices have been offered with provisions to compensate for expansion and to withstand pressure and temperature these cannot be readily or completely disassembled.

This invention has particular application to oil refining processes where one or both of the mediums to be handled contain solids which tend to deposit out or where the mediums are likely to decompose to form solids. Typical of these mediums would be the discharge from a cracking or reforming still, the heavy tar from a cracking operation, and the asphalt produced by vacuum distillation. Where any of these fluids is to be handled the exchanger must be easily disassembled to allow for cleaning. My invention provides for the easy disassembling of the inner tube connections at one or both ends to permit the ready withdrawal of the inner tubes.

Other and more specific objects will appear as the following description of a preferred and practical embodiment of my invention proceeds.

In the drawings which accompany and form a part of the following specification and throughout the several figures of which the same characters of reference have been employed to designate identical parts:

Figure 1 is a side elevation of a heat exchanger embodying the principles of my invention, the middle portion being broken away;

Figure 2 is an end view of the heat exchanger illustrated in Figure 1;

Figure 3 is the broken vertical sectional view of a portion of the heat exchanger illustrated in Figure 1 showing the inlet and two of the intermediate return bends;

Figure 4 is a section taken along the line 4—4 of Figure 3;

Figure 5 is a section taken along the line 5—5 of Figure 3;

Figure 6 is a sectional view through one of the intermediate return bends in an alternative form 10 of the invention; and

Figure 7 is a sectional view showing a modified form of connection between an inner tube and the return bend.

Referring now in detail to the several figures, the numeral 1 represents in general a heat exchanger consisting of vertically-stacked rows of double pipes each consisting of an outer tube 2 and an inner tube 3, said tubes being preferably coaxial and of such relative size as to leave an annular space within the outer tube. It will be understood that the double pipes may be optionally arranged in horizontal rows if convenience of installation so requires without affecting the operation of the exchanger. For purposes of 25 illustration the vertical arrangement is shown and subsequent references relate to the vertical arrangement.

In the illustrated form of the invention the outer tubes 2 are secured in tube sheets 3 in any suitable manner as by welding or by expanding and the tube sheets are shown as being divided into small individual sections each receiving four tubes arranged in side-by-side pairs. The extent of the tube sheets and the number of tubes received by them is, of course, a matter of choice or design and not affecting the patentability of the invention. At the inlet and outlet the tubes 2 are received in small tube sheets 4, each receiving two side-by-side tubes.

Figure 3 shows that the inner tubes 3 of successive rows project freely through the outer tubes, and being a little longer they extend into chambers 5 and 6 formed within headers 7. These headers might be integral castings or stampings, but in the interest of manufacturing economics they are shown as made up of three sections 8, 9, and 10. The headers are bolted to the adjacent tube sheets in fluid-tight manner, a gasket 11 intervening. Each projecting tube end is expanded or threaded in permanent and fluid-tight manner into end fittings 13. Where the tubes are expanded into the end fittings the fittings are preferably grooved so that 55

in the expanding operation, the tube metal will flow into the grooves forming the shoulder 12 and improving the tightness of the metal-to-metal joint. The end fittings consist of a sleeve portion 16 engaged with the ends of the inner tubes, having parallel ears 17 and 18 at diametrically opposite points, leaving a space in between. The outer ends of the sleeve portions 16 are internally flared as at 19 forming a seat for the correspondingly tapered ends of the U-bend 20. The U-bend bridges the space between vertically adjacent inner tubes and lies between the ears 17 and 18 of vertically adjacent fittings 13.

The ears 17 and 18 are formed with slots 21 through which extend the ends of the locking element or dog 22, see Figures 3 and 5. The dog has a threaded aperture 23 receiving a screw bolt 24, the lower end of which bears against the shoulder 25 formed on the U-bend. The entire fittings 13 including the ears 17 and 18 are sufficiently narrow to freely pass through the outer tubes 2 in the act of withdrawing the inner tubes to which the said fittings are permanently attached.

25 In the act of assembling, the U-bends are pushed into place, the dogs 22 put in position one at a time, of course, with their ends projecting through the slots 21, and the bolts 24 are then inserted and turned down until they abut the shoulders 25 on the U-bends. At this time the adjustment will be loose but by continuing to screw down the bolts 24 the cross bars 22 will back out until their ends engage the outer ends of the slots 21, whereupon the bolts will press rigidly 35 against the U-bend forcing the tapered ends of the same into fluid-tight engagement with the tapered ends of the fittings 13.

For taking out the inner tubes the process will be reversed. After the U-bends have been removed the tubes may be individually withdrawn.

With regard to the first and last double pipes in the series, the respective inlet and outlet ends of the outer tubes of which are permanently connected to the tube sheets, it is merely necessary to remove the U-bend at one end of the inner tube and then to disconnect bolts 26 and header 27, whereupon the inner tube may be withdrawn in an outward direction. It will be observed from the several figures that one end 50 of the inlet and outlet tubes, and both ends of the intermediate tubes are free-floating so that the inner tubes may expand freely under differences in temperature without setting up any strain in the structure of the heat exchanger.

55 For reasons of economy of size and material in the tube sheet and header construction, the axes of vertically adjoining tube assemblies 2, 3, and 5 are in divergent rather than parallel relationship with one another. The axes of horizontally 60 adjoining tube assemblies remain however in parallel relationship. The flared seats of the end fittings in cooperation with the tapered ends of the return bends adjust themselves to accommodate the pitch or divergence of the interconnected tubes without impairing the tightness of the joints. The joint between the end fittings and the U-bend may also be spherical in contour rather than conical as indicated in Figure 7, in which 39 is the spherical seat in the coupling and 70 40 the spherical end on the U-bend.

Figure 2 shows that the fluids which are to be placed in heat exchanging relation enter respectively by the inlets 28 leading to the inner tubes, and 29 communicating with the outer tubes, and 75 that the fluids leave the heat exchanger by way

of the respective outlets 29' and 30. Insofar as the structure of the apparatus is concerned and as affecting patentability, it is immaterial whether the fluids enter from the bottom or the top or whether they travel in parallel or contra-flow directions.

Referring to Figure 5, it will be observed that the header 7 is provided with an internal baffle 31, forming a vertical ridge or partition 32 and diverging in opposite directions so as in part to 10 bisect the interior of the header and to guide the flow of the fluid streams emerging from and entering the outer pipes. The baffle is preferably vented as at 32' to permit access of liquid to the otherwise blind space 33 and to equalize pressure 15 both inside and outside of the baffle. The purpose of the baffle is to prevent substantially lateral impact of the two parallel flow streams as they enter the header 7, and to direct them in an approximation to streamlined flow. The baffle in 20 cooperation with the U-bend forms passages which approach uniformity in cross section. The turbulent flow condition which would otherwise be set up in this zone by the interfering action of the two parallel streams is avoided to a large 25 extent by the interposition of this dividing baffle. Elimination of frictional loss which is reflected in power costs has a definite economic value.

In further expansion of this baffle's function, it 30 has been found in actual practice that unless some means is used to direct two parallel streams in an individual header, that the pressure losses due to impact of the opposing streams are high.

The modified form of the invention illustrated 35 in Figure 6 proposes to connect the ends of vertically adjacent inner tubes to tube sheets at one end substituting said tube sheets for the removable U-bend illustrated in connection with the first described form but leaving the other ends of 40 the inner tubes detachably connected to the removable U-bends 20.

Figure 6 shows that the outer tubes 2 are connected to a tube sheet 3' similar in all respects to that illustrated in connection with Figure 1 and 45 the inner tubes 3 which project a slight distance outwardly of the outer tubes, are connected to a tube sheet 34 which preferably lies against the tube sheet 3' in gasketed relation and occludes the ends of the outer tubes. In place of the 50 header 7 it is only necessary to connect the vertically adjacent inner tubes by means of a U-bend 35.

For taking out the inner tubes 3 individually, it is necessary to divide the tube sheet 34 as at 36. 55 Inasmuch as no header is provided, the outer tubes are interconnected by abutting nozzles 37 and 38.

In disassembling this form of the invention it is necessary only to remove the U-bend 20 from 60 two vertically adjacent inner tubes as fully described in connection with the first form of the invention. The U-bend 35 may then be grasped and the vertically adjacent pair of inner tubes 3 pulled out at the same time. If it is desired to 65 withdraw them individually, the U-bend 35 is taken off and either portion of the tube sheet 34 is drawn out together with the attached inner tube. The substitution of the tube sheet 34 for the construction shown in connection with Figure 3 does 70 not materially defeat the capacity of the inner tubes to expand for they are free-flowing at the opposite end.

While I have in the above description disclosed what I believe to be a preferred and practical 75

embodiment of the invention, it will be understood to those skilled in the art that the details of construction as shown and described are by way of example and not to be construed as limiting the scope of the invention as claimed.

5 What I claim is:

1. A heat exchanger comprising a plurality of double pipe elements arranged in rows, each including an inner tube and a surrounding outer tube, said tubes being arranged to define an annular space between them, the ends of outer tubes at one end of said exchanger being supported by a tube sheet and opening in the outer face of said tube sheet, a header secured against said tube sheet defining therewith a chamber with which two or more adjacent pair of outer tubes communicate, means for connecting the inner tubes of each of said pairs at said end of said exchanger comprising coupling members fixed to said inner tubes and of such size as to permit said inner tubes to be withdrawn through said outer tubes, a return bend for the inner tubes of each of said pairs having its ends received by said coupling members, said coupling members including clamping means for securing said return bends in place, a baffle within said header between adjacent re-

turn bends for preventing lateral circulation of the liquid within said header and means for independently serially connecting the inner tubes of said rows and the outer tubes of said rows at the opposite end of said exchanger.

2. A heat exchanger comprising a plurality of double pipe elements arranged in rows, each including an inner tube and a surrounding outer tube, said tubes being arranged to define an annular space between them, said double pipe elements being serially connected both as to the inner and outer tubes, the outer tubes at both ends being supported by tube sheets and opening into the outer faces of said tube sheets, and connecting devices at one end of a pair of adjacent inner tubes comprising a removable return bend permitting said inner tubes to be withdrawn from said outer tubes and means for securing said return bend to said inner tubes, a tube sheet receiving the opposite ends of said inner tubes, said last named tube sheet lying against the adjacent tube sheet which supports the outer tubes and occluding said outer tubes, a return bend secured to the tube sheet receiving said inner tubes and a lateral connection between said outer tubes.
